UNITED STATES PATENT OFFICE

ALBERT R. McMULLIN, OF NEW YORK, N. Y.

CARRYING MECHANISM FOR CENTRIFUGAL CONCRETE PIPE MACHINES

Application filed December 23, 1931. Serial No. 582,797.

This invention relates to improvements in bucket-carrying mechanism for centrifugal concrete pipe machines.

One of the objects of this invention is to improve the operating conditions which occur when the bucket in a concrete pipe making machine of the centrifugal type is employed as the supporting element for the trowelling member by increasing the stability and resistance to canting action developed by the bucket during such trowelling action, and also to improve the operating conditions encountered during the travel or traversing of the bucket-carrying carriage by so arranging the wheels of the carriage in relation to the rail members that the tracks on which the wheels run will be protected from concrete dropped from the bucket or splashed from the floor, which in machines employed prior to my invention often interfered with the movement of the carriage, causing jamming of the wheels, delay, extra work in cleaning, and often necessitating stoppage of the machine.

With these and other objects in view, the invention comprises the combination of members and arrangement of parts so combined as to co-act and co-operate with each other in the performance of the functions and the accomplishment of the results herein contemplated, and comprises in one of its adaptations the species or preferred form illustrated in the accompanying drawing, in which:

Fig. 1 is a view in side elevation of a centrifugal concrete pipe making machine embodying my invention;

Fig. 2 is an end elevation of the machine shown in Fig. 1, and

Fig. 3 is a section on the line 3—3 of Fig. 1 looking in the direction of the arrow.

Referring now to this drawing which illustrates a preferred embodiment of my invention, 1 indicates a concrete base on which is suitably mounted rail members A comprising heavy I-beams. Heretofore the wheels of the carriage have travelled on the inside of the bottom flange, and concrete dropping from the bucket or splashing from the

floor lodged on the wheel tracks and interfered with the movement of the carriage. By my invention, I provide spaced parallel rails having wheel channels A' provided with track-portions a comprising the outside bottom flanges of the rail members. These flanges are arranged on the outer sides of the webs a' and are spaced from the upper outside flanges a² a sufficient distance to permit a slight clearance above the front and rear 55 wheels G and H which will enable traverse on such wheels of the carriage B for the bucket C. Said bucket is mounted centrally of the carriage and disposed centrally between the rails A and is overhung on the 60 carriage to permit filling, in its "out" position, and insertion thereof into the mold F when in its "in" position.

As shown, the bucket C is rotatably mounted, to permit dumping, on a shaft S disposed along the longitudinal center of the carriage and rotatable in bearing yokes B'—B₂ of a width greater than the space between the rail members A. Said yokes extend across the rail members A and have wheel mounting portions b on the outside of said rail members. The wheels are mounted on shafts b' attached to and extending inwardly from said portions b, and suitable mechanism M, forming no part of this invention is employed 75 in turning the bucket in the dumping operation.

Said bucket is conventionally mounted with its center line eccentric to the axis of the mold F and has mounted thereon a trowelling blade C' which is employed for trowelling or compacting the concrete during the spinning of the mold and after the concrete dumped by the bucket has been 80 centrifuged in said mold which is spun by any suitable mechanism. As shown, the mold is rotatably mounted on wheels W mounted in trunnions t, the mold F being provided with circular tracks T and being rotated by a shaft S' turned from a motor M' through suitable 85 transmission mechanism. As shown, motion is transmitted by gear g on the motor shaft meshing with gear g' on shaft s on which is mounted one element of a transmission 90 100

mechanism comprising members g^2 and g^3 and motion is transmitted through these members to shaft s' and thence by gear g^3 , chain g^4 and gear g^5 to shaft S' .

5 The bucket-carriage B with bucket C mounted thereon travels forward along rails or tracks a from the "out" position where the front wheels H touch the stoppers E . This travel or traverse is for the purpose of 10 carrying concrete which has been taken into the bucket at the "out" position, to the interior of the mold F . The concrete is discharged from the bucket into the mold when the carriage has reached the "in" position.

15 In performing this traverse, the carriage wheels travel along the outside bottom flanges of rails A , and since the wheels have very little clearance between the top and bottom flanges of the rails, it is desirable that the 20 wheel tracks be kept clean and free from obstructing matter, and particularly from pieces or particles of concrete that fall from the bucket above said tracks. It will be understood that when particles of concrete 25 or other matter get under the tread of the wheels, such particles tend to raise the wheels causing a jamming thereof against the top flanges of the rail members.

30 In machines of this type prior to applicant's invention, the wheels ran on the inside flanges of the rails and concrete dropping from the bucket, concrete chutes or splashing from the floor readily got on to the wheel tracks and jammed the wheels, thereby interfering with movement of the carriage, and by 35 my invention this trouble and difficulty has been eliminated because the bucket being disposed in the middle of the carriage, concrete dropping therefrom falls in the middle or 40 between the tracks, and in so constructing the carriage that the wheels travel on the outside flanges of the rails, the webs of the rails protect the wheels and tracks from such spilled concrete and there is little likelihood 45 of concrete getting on to the rails to obstruct the same and causing faulty operation, and this method of construction thus gives improved operating conditions.

50 It will be understood also that the carriage in my improved construction may be made of greater width thereby increasing its stability and resistance to canting stress or action which is developed by the bucket when its trowelling operation is being performed.

55 Aligning rollers r are also preferably mounted to rotate horizontally on stub shafts r' on the under side of the carriage B and bear or roll along the inner edge of an inner top flange a^3 .

60 As many changes could be made in the above construction and many apparently widely different embodiments of this invention could be made without departing from the scope thereof; it is intended that all matter contained in the above description or

shown in the accompanying drawing shall be interpreted as illustrative and not in a limiting sense.

Having described my invention, I claim:—

1. Bucket-carrying mechanism for centrifugal concrete pipe-machines embodying, in combination, a pair of rail members, each having extending outwardly therefrom wheel channels composed of a vertical web portion, an outwardly extending track portion, and an outwardly-extending top-member, a carriage traversable along said rails and having a body portion extending laterally across said rail members and provided with wheels mounted thereon to extend inwardly into said outwardly-disposed wheel channels, and a concrete bucket mounted on said carriage between said rails. 70

2. Bucket-carrying mechanism for centrifugal concrete pipe-machines embodying, in combination, a pair of rail members, each comprising a plural flanged beam and having extending outwardly therefrom wheel channels composed of a vertical web portion, an outwardly extending bottom-flange track portion, and an outwardly-extending top-flange, a carriage traversable along said rails and having a body portion extending laterally across said rail members and provided with wheels mounted thereon to extend inwardly into said outwardly-disposed wheel channels, and a concrete bucket mounted on said carriage between said rails. 80

3. Bucket-carrying mechanism for centrifugal concrete pipe-machines embodying, in combination, a pair of rail members, each comprising a plural flanged beam and having extending outwardly therefrom wheel channels composed of an outwardly extending bottom-flange track portion, a vertical web portion and an outwardly extending top flange, a carriage traversable along said rails and having a body portion including yokes extending laterally across said rail members and having mounted therein between the side edges thereof a rotating shaft, and a concrete bucket mounted on said shaft and located between said rails. 90

In witness whereof, I have signed my name to the foregoing specification. 95

ALBERT R. McMULLIN.
